(57) **CLAIM**

The ornamental design for an egg packaging, as shown and described.

DESCRIPTION

FIG. 1 is a perspective view, taken from the front, top, and a first side, of an egg packaging, in accordance with our new design.

FIG. 2 is a perspective view, taken rear, top, and a second side, of the egg packaging shown in FIG. 1.

FIG. 3 is a top plan view of the egg packaging shown in FIG. 1.

FIG. 4 is a front elevation view of the egg packaging shown in FIG. 1.

FIG. 5 is a bottom plan view of the egg packaging shown in FIG. 1.

FIG. 6 is a rear elevation view of the egg packaging shown in FIG. 1.

FIG. 7 is a side elevation view of the egg packaging shown in FIG. 1, taken from the left side of FIG. 1; and, FIG. 8 is a side elevation view of the egg packaging shown in FIG. 1, taken from the right side of FIG. 1.

1 Claim, 5 Drawing Sheets
